UNITED STATES PATENT OFFICE.

GEORGE MUNGER, OF NEW HAVEN, CONNECTICUT, ASSIGNOR TO HIMSELF,
L. CANDEE, AND J. E. P. DEAN, OF SAME PLACE.

IMPROVEMENT IN CHALK-ERASERS.

Specification forming part of Letters Patent No. 33,684, dated November 5, 1861.

To all whom it may concern:

Be it known that I, GEORGE MUNGER, of New Haven, in the county of New Haven and State of Connecticut, have invented a new and Improved Rubber, the same being designed for rubbing off chalk-marks from blackboards, cleaning windows, and for similar or analogous purposes; and I do hereby declare that the following is a full, clear, and exact description of the same, reference being had to the annexed drawings, making a part of this specification, in which—

Figure 1 is a perspective view of my invention. Fig. 2 is a central transverse section of the same.

Similar letters of reference indicate corresponding parts in the two figures.

The object of this invention is to obtain a simple and durable device by which chalk-marks may be rubbed off from blackboards without the aid of moisture, the invention also serving as an excellent device for rubbing and cleaning the glass of windows, mirrors, &c.

The invention consists in having a series of strips of chamois or sheep skin or other similar soft leather or cloth fitted in a block or holder, as hereinafter described, to effect the desired end.

To enable those skilled in the art to fully understand and construct my invention, I will proceed to describe it.

A represents a rectangular block, which may be of wood and provided at its outer side with a handle B. The face side of the block A is grooved longitudinally, as shown at a, the grooves being at suitable distances apart and parallel with each other. The grooves a extend the whole length of the block A, and

in each groove a strip b of chamois or sheep skin or cloth is fitted, said strips being doubled or folded longitudinally and the folded edges being fitted in the grooves and secured therein by any suitable glue or cement. The grooves a are at such a distance apart and the leather strips b of such a width that the latter will completely cover the face of the block A, as will be fully understood by referring to both figures. The strips b are the rubbing medium, and it will be seen that by having them fitted in the block A, as shown, a great wearing-surface is obtained, and in moving or operating the block A back and forth the strips b will move or vibrate back and forth and operate very efficiently in rubbing out chalk-marks or in polishing a surface, such as glass. A plain or smooth cushion, it will be perceived, would soon wear out, as a single thickness of the skin is all that is subjected to wear, whereas by my invention the whole width of the strips b require to be worn out before the implement is unfit for use.

The implement may be very cheaply constructed and new strips b may be applied to the block A whenever required.

Having thus described my invention, what I claim as new, and desire to secure by Letters Patent, is—

The fitting or securing of strips b of chamois or sheep skin or other similar or soft leather or cloth in a block A, substantially as shown, to form an improved article of manufacture for the purpose specified.

GEO. MUNGER.
